(57) **CLAIM**

The ornamental design for a lid with carry loop, as shown and described.

DESCRIPTION

FIG. 1 is a front view of an embodiment of a lid with carry loop, the carry loop shown in a downward position; FIG. 2 is a right side view of the lid with carry loop shown in FIG. 1;

FIG. 3 is a rear view of the lid with carry loop shown in FIG. 1;

FIG. 4 is a left side view of the lid with carry loop shown in FIG. 1;

FIG. 5 is a top view of the lid with carry loop shown in FIG. 1;

FIG. 6 is a bottom view of the lid with carry loop shown in FIG. 1;

FIG. 7 is a top front perspective view of the lid with carry loop shown in FIG. 1;

FIG. 8 is a top rear perspective view of the lid with carry loop shown in FIG. 1;

FIG. 9 is a front view of the lid with carry loop shown in FIG. 1, the carry loop shown in an upward position;

FIG. 10 is a right side view of the lid with carry loop shown in FIG. 9;

FIG. 11 is a rear view of the lid with carry loop shown in FIG. 9;

FIG. 12 is a left side view of the lid with carry loop shown in FIG. 9;

FIG. 13 is a top view of the lid with carry loop shown in FIG. 9;

FIG. 14 is a bottom view of the lid with carry loop shown in FIG. 9;

FIG. 15 is a top front perspective view of the lid with carry loop shown in FIG. 9;

FIG. 16 is a top rear perspective view of the lid with carry loop shown in FIG. 9;

FIG. 17 is a front view of another embodiment of a lid with carry loop, the carry loop shown in a downward position; FIG. 18 is a right side view of the lid with carry loop shown in FIG. 17;

FIG. 19 is a rear view of the lid with carry loop shown in FIG. 17;

FIG. 20 is a left side view of the lid with carry loop shown in FIG. 17;

(Continued)

FIG. 21 is a top view of the lid with carry loop shown in FIG. 17;
 FIG. 22 is a bottom view of the lid with carry loop shown in FIG. 17;
 FIG. 23 is a top front perspective view of the lid with carry loop shown in FIG. 17;
 FIG. 24 is a top rear perspective view of the lid with carry loop shown in FIG. 17;
 FIG. 25 is a front view of the lid with carry loop shown in FIG. 17, the carry loop shown in an upward position;
 FIG. 26 is a right side view of the lid with carry loop shown in FIG. 25;
 FIG. 27 is a rear view of the lid with carry loop shown in FIG. 25;
 FIG. 28 is a left side view of the lid with carry loop shown in FIG. 25;
 FIG. 29 is a top view of the lid with carry loop shown in FIG. 25;
 FIG. 30 is a bottom view of the lid with carry loop shown in FIG. 25;
 FIG. 31 is a top front perspective view of the lid with carry loop shown in FIG. 25; and,
 FIG. 32 is a top rear perspective view of the lid with carry loop shown in FIG. 25.
 The broken lines are shown for the purpose of illustrating parts of the article that form no part of the claimed design. Broken line features and surfaces adjacent to claimed areas defined by shading form no part of the claimed design.
